UNITED STATES PATENT OFFICE.

HJALMAR ERICKSON, OF CAMBRIDGE, MASSACHUSETTS.

MACHINE FOR CLEANING BOOK COVERS AND THE LIKE.

Application filed April 22, 1921. Serial No. 463,624.

To all whom it may concern:

Be it known that I, HJALMAR ERICKSON, a citizen of the United States, and a resident of Cambridge, county of Middlesex, 5 and State of Massachusetts, have invented an Improvement in Machines for Cleaning Book Covers and the like, of which the following description, in connection with the accompanying drawings, is a specification, 10 like characters on the drawings representing like parts.

This invention relates to a machine for finishing and cleaning articles which have been inscribed or ornamented with stamped 15 designs of artificial gold or similar color media. Such work is commonly used on book covers or "casings" and the machine here shown is particularly designed for finishing such covers after the stamping operation. A considerable amount of the 20 artificial gold adheres to the face of the cover at points exterior to the design and must be removed and by mechanism such as here described this operation is rapidly and efficiently performed.

My invention will best be understood by reference to the following description of one particular mechanical embodiment of the principles thereof shown by way of example 30 in the accompanying drawings, wherein:

Fig. 1 is a side elevation of the machine;

Fig. 2 is a plan with parts broken away;

Fig. 3 is an end elevation as seen from the right in the other figures; and

Fig. 4 is an end view on an enlarged scale 35 of a book cover such as the machine is adapted to operate on.

Referring to Fig. 3 of the drawings, the machine here shown is organized on a suitable base 5 along one side of which extends the standard 7 which supports on one side a frame-work 9 overhanging the base 5. This standard 7 may also support the bracket 11 which carries a power shaft 13 adapted to 40 be driven by a pulley 15 and herein also a shelf-like bracket 17 supporting an auxiliary frame-work 19 for certain of the component mechanisms as hereinafter described.

In the example of my invention here 50 shown the book cover or "casing" is fed over a suitable work support or table and acted upon by cleaning devices carried by the overhanging frame 9. Referring to Fig. 2 the work passes through the machine from 55 right to left and may be first acted upon by

a rotary brush 21, preferably having spirally arranged series of bristles as shown, which removes dust and dirt and the looser particles of the gold. From the brush 21 it passes to a series of rubbing devices and I 60 have herein shown four such devices 23 which may be in the form of rollers. The rubbing devices are formed or faced with any suitable material adapted to give a rubbing or abrading action of the desirable intensity. The rollers 23 shown in the illustrated example of the invention are made up of a series of rubber (caoutchouc) disks 25 65 alternating with smaller spacing washers 27 threaded on a suitable spindle 29 and secured by a nut 31. The disks 25, made of any suitable rubber compound such as is used for erasers, present a plurality of relatively narrow rubbing edges to the work. The rubbing devices are given a compound 70 motion over the work both longitudinally and transversely thereof and herein this is effected by rotating the same and at the same time reciprocating or oscillating the rollers 75 axially. Herein the brush 21 and the rollers 23 extend transversely of the path of the work and are journaled in the side members of the overhanging frame 9. Referring to Fig. 2, it will be seen that one end of each shaft or spindle 29, the upper in that figure, 80 telescopes in its journal 32 and the other end is feathered at 33 in a gear 35 journaled in the standard plate 7. The gears 35 mesh as shown in Fig. 1 and one of these gears 85 may be driven by gear 37 from the power shaft 13. The succession of rubbing rollers 23 are by this means rotated in opposite directions in contact with the work. To reciprocate the rollers 23 the ends of the shafts shown at the bottom in Fig. 2 may be extended and provided with grooved collars 39 90 fixed thereto with which collars cooperate the yoke shaped ends of oscillating levers 41 in the manner of the well known clutch shifting lever. In the present example of the invention there are four rollers 23 and two levers 41, each operating a pair of adjacent rollers and reciprocating them in opposite phase. Motion of the levers may be 95 effected in any convenient manner. I have shown them as mounted centrally on vertical shafts 43 stepped in the shelf-like bracket 17 and in an overhanging bracket 45 and to the ends of the shafts 43 projecting above 100 the bracket 45 are attached levers 47 which 105

110

in the present instance are connected by the link 49 so that the two levers may be operated as a unit. The levers are oscillated by a connecting rod 51 attached to the adjustable wrist pin 53 of a crank wheel 55 driven by a gear 57, as best illustrated in Fig. 1, from one of the gears 35. It will be understood that as the crank wheel 55 revolves the levers 49 will be oscillated in a horizontal plane through the connecting rod, similarly oscillating the levers 41 and adjacent rollers 23 will be reciprocated in opposite phase, this action being permitted by the splined connection thereof with their driving gears 35 and the telescoping mounting in the journal boxes 32.

To accommodate work of different thicknesses provision should be made for relative adjustment between the rubbing mechanisms, herein typified by the rollers 23, and the work support and in the example of the invention shown this is provided for by vertical adjustment of the work support relatively to the rubbing rollers which are stationary. Referring particularly to Fig. 3 of the drawings, the work support here illustrated consists of a suitable table 65 carried by the fixed flange 67 and the removable flange 69 of a plate 71 which is adjustably supported on the base 5 by means of a plurality of threaded posts 73 received in nuts 75 journaled in the base 5. On the nuts 75 are mounted suitable sprocket wheels 77 with all of which cooperates a chain 79 which may be driven by a sprocket 81 carried by hand wheel 83. It will be clearly understood that movement of the hand wheel will rotate all the nuts 77 and elevate plate 71 and consequently the table 65, maintaining the table constantly in a horizontal plane.

It will be understood that the table is adjusted in to such proximity to the rubbing rollers 23 that the work placed on the table will be acted upon by the rollers with desired pressure. To feed the work forward for action of the rubbing elements thereon suitable feeding means are provided. The rubbing devices 23 should move relatively to the work instead of merely moving with it in its feeding travel, and it will be noted that in the example of the invention shown certain of the rollers 23 even oppose the passage of the work. This is desirable if they are to rub off the gold therefrom by their motion relative thereto instead of perhaps merely aiding in feeding the work forward by friction without relative longitudinal motion and consequent rubbing off of the gold. In the present instance (see Fig. 3) the flanges 67 and 69 provide bearings for a number of feed rolls 85, the upper faces of which project up through the work support or table 65. These rolls may be provided with sprockets 87 connected by a

chain and the roll at the left has a sprocket 88 with which cooperates a chain driven (see Fig. 2) by a driving sprocket 89 which takes its motion through a suitable train of reduction gearing 91 from the shaft of the crank 70 wheel 55. The driving sprocket 89 is, of course, fixed on the stationary standard 7, but this driving connection permits of the desired adjustment of the work support vertically. To hold the work to the driving rolls 85 opposed idler rolls 93 may be provided, the journals (see Fig. 1) 95 of these rolls being mounted for vertical sliding movement in the side members of the frame 9 and being pressed down toward the driven rolls 85 by means of springs 97. Threaded rods 99 project upwardly from the journal boxes and provide for adjustment of the pressure by means of the nuts 101.

In Fig. 4 I have shown a book cover such as the machine is particularly designed to operate on, comprising the side boards *s* and the cloth cover *c*, the two side boards being connected by the portion *b* of the cover which forms the back of the bound book. Usually the cloth is stamped over one of the sides *s* and along the back *b*. To support the back *b* for operation of the rubbing elements thereon, a portion of the table is made adjustable so that it may be raised beyond the level of the rest and enter the space between the two boards *s* and support the back *b* in the plane of the sides. Herein (see Fig. 3) flanges 103 on the plate 71 have adjustably mounted thereon the brackets 105 which may be vertically moved by set screws 107 and these brackets serve to support a removable table section 109 somewhat above the level of the rest of the table 65, as shown in Fig. 3, to support the flexible back *b* of the book cover in the plane of the sides so that one of these sides and the back may be simultaneously acted upon by the rubbing devices. To facilitate the passage of the book cover through the machine and prevent the flexible back from being by any possibility displaced the supporting surface 109 for the back may be in the form of a continuous strip (see Fig. 2) extending from one end of the machine to the other, the feed rolls 85 being suitably grooved at 111 (Fig. 3) to receive this strip. The brackets 105 are of sufficient width to accommodate various sizes of supporting strips 109 to suit the particular work at hand.

As best shown in Figs. 1 and 2, it is preferable to extend the table 65 at some distance at the intake side of the machine to facilitate the insertion of the covers.

By reference to Fig. 3 it will be clear that, since the frame 9 overhangs the table from the one side thereof, the left hand side in that figure, and since the rubbing devices and pressure rolls 93 are supported by said

frame, there is provided an unobstructed space along the right hand side of the machine substantially in the plane of the table 65, there being no standard 7 on that side. 5 Consequently although the machine may be relatively narrow in width it will accommodate various sizes of covers. Ordinarily the front cover and the back of the book are stamped and the back cover does 10 not need cleaning but may project out from the open space to the side of the machine as will be clearly understood from Fig. 3 particularly by observing the position of the strip 109 which supports the back of the 15 cover or casing. It will also be clear that the adjustment of the parts is effected as a whole by adjustment of the table and of the rolls 85 moving with it, the whole being effected by the hand wheel 83. There will 20 be no need of separately adjusting the various rubbing devices and for ordinary purposes the resilient mounting of the pressure rolls 93 will accommodate them to the work. 25 I will next describe briefly the operation of the particular machine shown in the drawings as an example of my invention. Referring to Fig. 3, a book cover as shown in Fig. 4 is inserted in this end of the machine, the front cover of the book resting on the table 65 and the back 6 being supported in the same plane as the outside of the cover by the support section 109 which has been properly adjusted in accordance 30 with the thickness of the boards 8. The entire work support with the feed rolls is vertically adjusted to provide for proper pressure on the work of the vertically fixed rubbing rollers 23 as the work passes 35 through the machine and proper tension is applied to the springs 97 so that the driven rolls 85 and the opposed idler rolls 93 will grip the cover to feed it forward through the machine from right to left, viewing 40 Fig. 2. The book cover passing through the machine is first cleaned by the rotary brush 21 and then is acted upon successively by the rubber disks 27 on the rollers 23. These disks rotate in contact with the 45 work and in the example shown the disks of successive sets rotate in opposite directions and the speed of rotation is different from the feeding speed of the work so that a true rubbing action is effected. During 50 their rotation the disks are oscillated axially of the rolls so that no part of the cover is skipped and a compound rubbing movement over the cover of the narrow edge of the disks is effected which is very effective for loosening and removing the superfluous stamping material which it is 55 desired to remove. 60 A transverse shaft 113 provided with a hand wheel 115 and a gear 117 meshing 65 with one of the gears 35 may be provided to

permit the machine to be turned over by hand when desired.

Having thus described in detail the particular form of my invention shown by way of example in the accompanying drawings, 70 the principles exemplified thereby which I claim as new and desire to secure by Letters Patent I shall express in the following claims.

Claims.

1. A machine for cleaning surplus leaf from stamped book covers and the like comprising a work support, means for advancing the work over the support and a plurality of rubbing devices operating on the work as it advances, each contacting with the work along a narrow transverse zone, and means to give said devices rolling rubbing motions in opposite directions to bend, break and lift the surplus leaf. 75

2. A machine as defined in claim 1 wherein the devices are simultaneously reciprocated transversely of the work.

3. A machine for cleaning surplus leaf from stamped book covers and the like comprising a work support, means for advancing the work over the support and a plurality of rubbing devices operating on the work as it advances, each contacting with the work along a narrow transverse zone, and means simultaneously to reciprocate said devices transversely of the work and to give them a rubbing rolling motion to bend, break and lift the surplus leaf. 90

4. A machine for cleaning surplus leaf from book covers and the like comprising a vertically adjustable table to support the work, feed rollers projecting therethrough and moving with the table and a frame projecting above the table and carrying opposed feed rollers and driven rubbing devices for operating on the work. 100

5. A machine for cleaning surplus leaf from book covers and the like comprising a vertically adjustable table to support the work, feed rollers projecting therethrough and moving with the table, a standard projecting at one side of the table, opposed feed rollers and driven rubbing devices supported by said standard in overhanging relation to said table to provide an open space at the other side between the table and said supported elements whereby to accommodate covers of various widths and permit the back cover to project loosely at the side of the machine. 110

6. A machine for cleaning surplus leaf from book covers and the like comprising a work support, driven cleaning devices opposing said support and overhung from a side of the support and means for advancing the work over the support, the whole assembly presenting along one side an unobstructed space substantially in the plane of said support whereby the machine may operate. 115 120 125 130

ate on covers of different width and the back cover may project through said space to the side of the machine.

7. A machine for cleaning surplus leaf from book covers and the like comprising a vertically adjustable table to support the work, feed rollers projecting therethrough and moving with the table, a portion carried by said table and adjustable relatively thereto for supporting in the plane of the sides a book cover which is placed on the table, and a frame projecting above the table and carrying opposed feed rollers and driven rubbing devices for operating on the work.
8. A machine for cleaning surplus leaf from book covers and the like comprising a vertically adjustable table to support the work, feed rollers projecting therethrough and moving with the table, brackets vertically adjustable relatively to said table, and a removable longitudinal strip carried thereby for supporting in the plane of the sides a book cover which is placed on the table, and a frame projecting above the table and carrying opposed feed rollers and driven rubbing devices for operating on the work.
9. A machine of the class described comprising a table and a feed roller journaled beneath the table and projecting there-

through, a frame, a pressure device carried by said frame opposing the roll, a rubbing device carried by the frame opposite the table, said table and frame being relatively vertically adjustable and means for driving said roller and rubbing device, and said table being provided with a relatively adjustable portion for supporting in the plane of the sides the back of a book cover which is placed on the table.

10. A machine for cleaning surplus leaf from book covers and the like comprising a support over which the cover is advanced and driven rubbers moving with a compound longitudinal and transverse movement relatively to the surface of the cover as it is advanced.

11. A machine for cleaning surplus leaf from book covers and the like comprising a support over which the cover is advanced and a driven rubber presenting a narrow edge to the work moving with a compound longitudinal and transverse movement relatively to the surface of the cover as it is advanced.

In testimony whereof, I have signed my name to this specification.

HJALMAR ERICKSON.
